UNITED STATES PATENT OFFICE.

REUBEN H. BROWN, OF NEW HAVEN, CONNECTICUT.

CALIPERS.

SPECIFICATION forming part of Letters Patent No. 288,771, dated November 20, 1883.

Application filed May 3, 1883. (No model.)

To all whom it may concern:

Be it known that I, REUBEN H. BROWN, of New Haven, in the county of New Haven and State of Connecticut, have invented certain new and useful Improvements in Calipers, of which the following is a specification, reference being had to the accompanying drawings.

My invention is designed for use with ordinary measuring-calipers, or with that class of instruments known as "micrometer-gages," and is designed to increase their effectiveness, to give them greater nicety of action, and to permit of their readjustment after their accuracy has been destroyed by wear.

15 Figure 1 is a side view of my invention, showing its application to a micrometer-gage or calipers. Fig. 2 is an edge or end view of the same. Figs. 3 and 4 show details of the invention.

20 Similar letters of reference indicate similar parts in the respective views.

A is a block, threaded to receive the screw B. To the block A are pivoted or hinged the legs C C. The lower end of the screw B is made to turn freely in a yoke, D, being secured and adjusted thereto by means of an upper nut, a, and a lower nut, b. Each end of the yoke is slotted to permit the entry of a leg of the calipers, and provided with a roll, c, 25 adapted to rest upon the outer edge of a leg, and to turn freely upon its pivot c.

30 A spring, E, (shown detached in Fig. 3,) is clamped between the nut a and the top of the yoke D, the outer ends of the spring being free and conforming to the curve of the inner edges of the legs. The spring E acts to extend the instrument and to keep the outer edges of the legs in contact with the rolls c. A perspective view of the yoke D is shown in 35 Fig. 4.

40 From the top of the block A extends a cylindrical graduated part, d. The upper portion of the screw B is provided with a cylindrical cap, F, which fits neatly over the cylindrical part d of the block. The lower end of the cap F is beveled and vertically graduated to act in connection with the graduated marks of the part d, as in the micrometer-gage now in use. The head of the cylindrical cap F is 45 secured to the top of the screw B by means of a screw, e.

On turning the cylindrical cap F the screw B is revolved and the yoke D elevated, the spring E expanding the instrument. The rolls c slide upon the outer edges of the legs 55 C C, said edges being so curved or shaped that the points f f of the legs are moved in a perfectly regular manner. To contract the instrument the cap F must be revolved in the opposite direction, and the rolls c, sliding up- 60 on the curved outer edges of the legs, will cause the legs to approach. Should the points f f become worn, the cap F must be turned until the points meet. The screw e must now be loosened and the cap F turned until its zero- 65 point corresponds with that of the graduated cylindrical portion d of the block A. On tightening the screw e the instrument is readjusted and again in perfect order.

I claim as my invention—

70 1. The combination, in calipers, of a threaded rod having its end turning in a yoke, a nut traveling on said threaded rod and having legs pivoted thereto bearing against rolls located in the outer ends of the yoke, and a free- 75 ended spring clamped to the yoke and having its free ends curved to conform to the inner contour of the legs and exerting an unvarying pressure on the same, irrespective of their degree of adjustment, substantially as set forth. 80

2. The combination, in calipers or micrometer-gages, of a block or nut having a graduated cylindrical extension, a screw, a cylindrical graduated cap secured to the screw and fitting over the said cylindrical extension, legs pivoted or hung to said block, a yoke connected to the lower end of the screw, and in which said screw freely turns, said yoke being stationary with respect to said nut and legs, a free-ended spring for expanding the legs, and 85 rolls supported in the respective ends of the yoke and resting upon the outer edges of the legs, substantially as set forth.

In testimony whereof I hereunto set my hand and seal in the presence of two witnesses. 90

REUBEN H. BROWN. [L. S.]
